UNITED STATES PATENT OFFICE.

WILLIAM C. BAKER, OF NEW YORK, N. Y., ASSIGNOR TO THE BAKER HEATER COMPANY, OF SAME PLACE.

RAILWAY-CAR HEATER.

SPECIFICATION forming part of Letters Patent No. 439,287, dated October 28, 1890.

Application filed January 24, 1888. Serial No. 261,785. (No model.)

To all whom it may concern:

Be it known that I, WILLIAM C. BAKER, of the city, county, and State of New York, have invented an Improvement in Railway-Car Heaters, of which the following is a specification.

Railway-car heaters have been extensively introduced in which water is made to circulate through radiating-pipes in the car, which 10 pipes are connected with a coil in the fire-chamber. My patent, No. 374,336, granted December 6, 1887, illustrates a heater of this character. The coal for these heaters has usually been contained in the bin resting upon 15 the floor of the car or else in an elevated bin, as shown in my patent, No. 331,367, granted December 1, 1885; but in all instances it has been necessary to make use of a shovel to supply the coal into the fire-chamber. In doing 20 this the dust is liable to pass out into the car, and sometimes gases escape at the fuel-door.

My present improvement is for rendering the heater and fuel-supply more compact and 25 for passing the fuel into the fire-chamber without the use of a shovel, and this can be done while the heater is in a closed condition, and I also provide for introducing fuel in the ordinary manner, so that the fire can be fed 30 in case the elevated coal-bin becomes exhausted.

In the drawings, Figure 1 is an elevation of my improved heater with the elevated coal-bin, and Fig. 2 is a vertical section of the 35 same. Fig. 3 is a plan below the line xx , and Fig. 4 is a partial vertical section at the line yy , Fig. 3.

The water-heating coil A is within the fire-chamber B, and this is provided with a grate 40 C above the ash-pit D, and the whole is enclosed in a case E, having a door F to the ash-pit, as represented in my application, Serial No. 256,491, filed November 30, 1887, and at the top of the fire-chamber is a supply- 45 pipe G and safety-plate, and this safety-plate is pivoted and can be swung up within the casing K. I have represented these parts as best adapted to my present elevated coal-bin; but I do not limit myself in the use of said 50 elevated coal-bin to the details of the con-

struction of the heater. My said elevated coal-bin is formed of a case L, having at the top a supply-chute M and cover N, and the bottom thereof is conical or hopper-shaped, as at P, and the contracted opening Q at the 55 bottom of the hopper is directly over the supply-tube G, so that coal dropping from the elevated coal-bin will pass directly through such supply-pipe G, and I provide a valve R in the base of the elevated coal-bin, and the 60 same is preferably pivoted at one side, so that it can be turned up by a key or wrench S, introduced through a hole in the side of the casing, but preferably through the doorway when the door W is slid aside and set- 65 ting upon a square at the hinge or pivot of the valve, and the valve rests at its edges upon the shoulder or offset at the discharge-opening Q. Hence the weight of the coal closes 70 the valve, and it is opened by sufficient force to slightly lift the coal, and it is preferable to notch this door W at one side so as to close the same upon the shank of the key or wrench to keep the dust from passing out into the car.

Outside the coal-bin L is a casing T, attached at its lower end to the top portion of the safety-casing around the fire-chamber, and there is a space between the elevated coal-bin L and the case T, which forms a flue 75 for the escaping products of combustion from the fire-chamber, and at the top of the case T is a conical contraction U, that unites the case T and the smoke-flue V, and through this conical contraction U the supply-chute M 80 passes.

It will be apparent that the products of combustion as they pass up around the elevated coal-bin warm up the coal; but the heat is not sufficient to ignite the same, and these products of combustion escape by the flue V 90 through the roof of the car, as usual, and the supply-chute M may also pass through the roof or the side of the car, wherever most convenient for receiving the supply of coal.

The door W is fitted to slide in top and 95 bottom guides around the outside of the casing T, and it covers the opening through the casing T, and there is also an opening at this point through the lower portion of the elevated coal-bin support K, so that access is 100

given to the safety-plate H. Hence when coal is to be supplied to the fire the door W is turned aside and the safety-plate H unlatched, raised up, and thrown back, so as to open the space for the coal to pass down into the fire-chamber upon turning or moving the valve R, preferably after the door W has been closed, as aforesaid; and this safety-plate is closed (immediately after the supply of coal has been shut off) in the usual manner with the heaters heretofore constructed by me and before the door W is shut, and this door W gives opportunity for introducing fuel by a shovel should the supply of coal in the elevated coal-bin be exhausted.

The safety-plate H is of a size to fill the upper end of the supply-pipe G, and it is pivoted at opposite sides, as seen in Fig. 2, so that it may be swung up into the position shown in Fig. 4, and there is a spring-latch (see Fig. 4) to hold the safety-plate when closed down.

I find it convenient to make a long vertical opening through the case T and through the elevated coal-bin, as shown at X, and to introduce a frame at this point that joins the casing and coal-bin, and into this frame a plate of thick glass is introduced, and one or more vertical bars at the back of the glass prevent the coal coming into direct contact with such glass, but permit the attendant to see whether there is a sufficient supply of coal in the coal-bin. It is preferable to provide two of these frames and glasses at opposite sides of the elevated coal-bin in such positions that light is admitted at the back of the coal-bin, so that the height of the coal may be more easily inspected, even when the glasses may have become coated more or less with coal dust or soot; and it is preferable to introduce a mica window in the door W, as at

10, so as to be able to observe the quantity of coal admitted to fall into the fire-chamber.

I claim as my invention—

1. The railway-car heater having a fire-chamber and a supply-tube G above the same, in combination with the safety-plate H for closing the supply-tube, an elevated coal-bin and the support K for the same around the supply-tube, a case T around the elevated coal-bin, forming a flue between the same and the coal-bin for the products of combustion, the contracted top U to the said case, and a smoke-flue V and supply-chute for the coal-bin at the upper part thereof, substantially as set forth.

2. The elevated coal-bin having a hopper-shaped bottom and opening, in combination with a railway-car heater having a fire-chamber and a supply-tube G and safety-plate H, the support K for the coal-bin around the supply-tube and safety-plate, the casing T, with an opening therein, and the door W for giving access to the safety-plate and to the top of the fire-chamber, substantially as set forth.

3. The combination, with the railway-car heater having a fire-chamber and an inclosing-case, of an elevated coal-bin having an opening at the lower portion thereof above the supply-opening to the fire-chamber, a valve to shut off the supply of fuel, a safety-plate to the supply-opening of the fire-chamber, a case around the elevated coal-bin having an opening near the safety plate and valve, and a door to the same, substantially as set forth.

Signed by me this 23d day of January, 1888.
W. C. BAKER.
